UNITED STATES PATENT OFFICE

130,115

DESIGN FOR AN ILLUMINABLE WHATNOT

George Braun, Jr., Sappington, Mo.

Application February 20, 1941, Serial No. 99,134

Term of patent 7 years

To all whom it may concern:

Be it known that I, George Braun, Jr., a citizen of the United States and a resident of Sappington, in the county of St. Louis and State of Missouri, have invented a new, original, and ornamental Design for an Illuminable Whatnot, of which the following is a specification, reference being had to the accompanying drawing, forming part thereof.

Fig. 1 is a top plan view of an illuminable whatnot, showing my new design;

Fig. 2 is a front elevational view thereof;
Fig. 3 is a rear elevational view thereof;
Fig. 4 is a horizontal sectional view on the line 4—4 in Fig. 3; and

Fig. 5 is a fragmentary vertical sectional view on the line 5—5 in Fig. 4.

I claim:

The ornamental design for an illuminable whatnot, as shown.

GEORGE BRAUN, JR.
